UNITED STATES PATENT OFFICE.

CHARLES EDWARD BEYER, OF MAZATLAN, MEXICO.

CONCENTRATOR.

1,221,659.

Specification of Letters Patent.

Patented Apr. 3, 1917.

Application filed April 16, 1915. Serial No. 21,701.

To all whom it may concern:

Be it known that I, CHARLES EDWARD BEYER, a subject of the King of Great Britain, residing at Mazatlan, in Sinaloa, Mexico, have invented new and useful Improvements in Concentrators, of which the following is a specification.

This invention relates to concentrators, and its primary object is to provide a concentrator which will operate with maximum efficiency in either dry or wet concentration, and which while especially useful in dry concentration, as for the abstraction of gold from low grade alluvial or placer deposits in arid or semi-arid sections, may be employed in wet concentration with the use of a small quantity of water and without the necessity of employing a constant flow of water, as with concentrators of ordinary construction.

A further object of the invention is to provide a concentrator having a novel construction and arrangement of devices for securing a positive and efficient separation of the components of the material according to their specific gravities, the agitation of and carrying off of the sand and other particles liable to remain dormant and interfere with the free settlement of the gold or other metalliferous matter, and the discharge and collection of the concentrates at predetermined periods.

With these and other objects in view, the invention consists of the features of construction, combination and arrangement of parts herein fully described and claimed, reference being had to the accompanying drawings in which:

Figure 1 is a view in elevation looking toward one side of the concentrator.

Fig. 2 is a similar view looking toward the opposite side of the concentrator, with parts omitted.

Fig. 3 is a top plan view of the concentrator.

Fig. 4 is a similar view on an enlarged scale with the agitators and inclined deck plates removed showing clearly the combination of the riffles, screens and belt.

Fig. 5 is a vertical longitudinal section through the machine.

Fig. 6 is a view in elevation looking toward the rear or discharge end of the machine.

Fig. 7 is a vertical transverse section on line 7-7 of Fig. 1.

Figs. 8 and 9 are detail views of the intermittent mechanism for operating the belt.

Fig. 10 is a detail view showing a modification in the belt operating mechanism.

In carrying my invention into practice, I make the table of the concentrator in the form of an oblong rectangular box or casing 1, which may be constructed of wood or metal. That shown in the present instance is made of wood, and is suitably supported in the ordinary way upon four springs 2, arranged at or near the corners thereof, said springs assisting in maintaining the table in a normal position, while permitting reciprocatory or vibratory motion thereof. The table is inclined downwardly to a determined degree between its receiving and discharge ends, to facilitate the flow of the material to be treated by gravity, and may be reciprocated or vibrated by any preferred type of means. In the present instance I have shown a head motion mechanism 3 of ordinary construction, which may be a common crank and lever or eccentric and lever motion, which mechanism operates to periodically move the table rearwardly against the resistance of the springs 2 and head springs 4, said springs serving by their resiliency to move the table forwardly or return the same to normal position, a rapid reciprocatory or vibratory action of the table being thereby effected. Arranged within the box or casing, adjacent the opposite ends thereof are flanged pulleys or rollers 5 and 5^a over which travels a longitudinally extending endless belt or apron 6, preferably of pure rubber. The rollers 5 and 5^a are mounted on transverse shafts or axles 7 and 7^a extending exteriorly at the sides of the casing, the shaft 7 being journaled in fixed bearings, while the shaft 7^a is journaled in movable bearings 8 adjustable by means of set screws 9, whereby any slack in the belt may be taken up and the belt kept taut.

The outer face of the belt is provided with one or more transverse channels 9' extending its full width, and which may be of suitable depth, the said channels serving to receive the concentrates for conveyance by the belt or apron to the discharge point.

As shown, the upper stretch of the belt 10 moves in direct contact with the curved lower faces of a series of spaced, transversely disposed screens 11, and is held in close contact therewith by a series of trans-

versely arranged guide rolls or elements 11', while the lower stretch 12 of the belt travels over the rounded upper surfaces of transverse supports 13, preferably consisting of 5 metallic plates secured to suitable supporting blocks 14, the said supporting members 13 serving to prevent the lower stretch of the belt from flapping or moving unduly during the vibratory action of the concentrator, thus 10 insuring an easy working travel of the belt. A scraper or guard 15 composed of a transversely disposed plate is arranged to bear against the upper surface of the said lower stretch 12 of the belt in proximity to the roll 15 5', and serves to remove from the belt all adhering particles of the concentrates which may fall thereon, for discharge through the concentrates outlet 16 disposed at the bottom of the box or casing adjacent to the forward 20 end thereof.

The scraper blade or plate 15 is vertically movable in guide slots 17 in the sides of the box so as to automatically adjust itself to compensate for irregularities of surface in 25 the belt, and said blade or plate is held from endwise displacement by cotter pins 18 and yieldingly forced down into working engagement with the belt by springs 19. The concentrates are discharged from the belt at 30 the forward end of the box or casing upon an inclined delivery shelf 20 leading to the outlet 16. The screens 11 preferably consist of perforated boards or plates secured to rear cross strips 21, in advance of each of 35 which is a front cross strip 22, the said screens and cross cleats being suitably fastened to brackets 23 upon the side walls of the box or casing. The front cleats 22 terminate at their upper edges at a somewhat 40 lower level than the upper edges of the rear cross cleats 21, and, in addition to another cross cleat 24, form supports for the upper rear ends of inclined plates 25, the lower forward ends of which fit within recesses or 45 rabbets 26 formed in the rear edges of the screens 11, so as to terminate substantially flush with the upper surface of said screens. These plates in conjunction with the screens 50 11 form the deck of the concentrator, along which the material travels from end to end of the box or casing during the concentrating action, and it will be observed that the respective plates 25, which constitute sections of said deck, are inclined downwardly and forwardly, and thereby provide inclined 55 planes for the forward travel of the material by gravity in addition to the motion imparted thereto by the reciprocation of the concentrator, the relative arrangement of 60 the plates and screens 11 providing pockets 26' above said screens for the collection of the material behind riffles guarding said pockets, said riffles being formed by the cross cleats 21, by which the progress of the portions of 65 the material upon each section of the deck is

arrested for a predetermined period for an efficient concentrating action.

In practice, the material to be treated is fed into the box or casing at the upper end of the first deck section 25, and thence, 70 through the action of gravity and the reciprocatory or vibratory motion of the table, feeds forwardly, the material accumulating in each pocket 26' until it rises above the level of the adjacent riffle 21, over which it passes to the next forward inclined deck section, the concentrates gradually feeding downward within the pockets through the mass of material during the concentrating 75 action until they rest upon the perforated screens 11. The perforations of these screens are closed by the upper stretch 10 of the conveyer belt 6 except at predetermined intervals when the channels 9' pass beneath the screens, the concentrate then discharging 80 through the perforations in the screens into the channels 9, and being conveyed forward by the belt and finally deposited upon the shelf 20 for discharge by gravity through the concentrates outlet 16. A sufficient interval is thereby allowed to elapse at all 85 times during the agitation of the material within each pocket 26 between registration of channel 9 with the underlying screen to permit the concentrates to settle by 90 specific gravity for collection and discharge, the closing of the perforations in the screens by the belt insuring at all 95 times security against the discharge of any of the concentrates or material by the 100 screen at other periods or the loss of any of the concentrates, as will be readily understood. It will be apparent from the foregoing disclosure that the material feeding through the machine will be subjected to a series of concentrating actions, and that owing to the inclination of the deck surfaces between the pockets and riffles, and the consequent feed of the 105 material by gravity, as well as by a 110 rapid reciprocatory or vibratory action of the table, a free, rapid and effective turning over of the particles of material will be obtained, thereby insuring the collection of all of the gold or precious material in the sand, ore or other metalliferous matter in the dry concentration treatment of certain materials containing fine sand, however, the sand tends to pack within the 115 pockets 26' and lie dormant therein, thus 120 preventing the proper stratification of the elements of the material and passage of the heavier, metalliferous particles to the screens, it being customary in the ordinary 125 type of dry concentrators to displace this sand by blasts of air. For the purpose of keeping the material in the pockets thoroughly agitated, and insuring their proper stratification, I provide an agitator device above the lower portion of each sec- 130

tion of the deck, each agitator device comprising a suitable head, plate or backing member 27 provided with a multitude of spring wire fingers or tines which extend 5 down into the underlying pocket 26 and terminate just above the lower portion of the plate 25 and the associated screen 11. These agitators vibrate, in the reciprocation 10 of the concentrator, in a direction longitudinally of the machine, and the fingers or tines 28, add both to this vibratory action and to the inherent spring action thereof, loosen up and turn over the particles of material, thereby preventing the sand from 15 packing or remaining dormant, and permitting the heavy particles of the precious material to feed downward to the screen, thus making provision for the collection, during the transit of the material along 20 the length of the table of the metalliferous particles capable of being separated and concentrated. The agitators are mounted upon transverse shafts 29 journaled in suitable bearings 30, the ends of the shafts extending 25 beyond the sides of the box or casing and having mounted thereon weighted pendulum levers 31 movable in guards or casings 32. During the rapid reciprocatory motion of the machine these weighted pendulum 30 levers are set into action, their action being limited by contact with the sides of the guards or casings 32, by which, in connection with the spring action of the tines or fingers, an automatic operation of the 35 agitators upon the material is secured without the necessity of employing auxiliary power for the purpose.

The belt 6 is periodically actuated by means of intermittent feed mechanism comprising a ratchet wheel, composed of a pair 40 of ratchet disks 33 and 34 fixed to one end of the shaft 7 and suitably fixed to each other. The teeth of these ratchet disks, which are equally spaced, are arranged in 45 a staggered relation or so that the teeth of one disk lie on lines between the teeth of the other disk, thus enabling a wheel of fine pitch to be obtained without the necessity of employing a wheel having very closely 50 related and delicate teeth. Arranged to engage the teeth of the respective ratchet disks are pivoted spring pressed dogs or pawls 35 and 36, carried by a pendulum lever 37 loosely mounted to swing upon the shaft 7 55 as an axis in a direction longitudinally of the machine. The lower end of this lever, carries a ball or weight 38 and the swing of said lever is restricted and its travel regulated by means of set screws or adjustable 60 stop devices 39 supported by brackets 40 on the sides of the box or casing, the construction being such that during the reciprocatory motion of the concentrator and during its travel in one direction the lever will be operated, causing the pawls 35 and 36 to en-

gage the teeth of the ratchet wheel and turn said wheel a prescribed distance in a feeding direction, while upon the travel of the concentrator in the opposite direction the lever will return to normal position and its 70 dogs will slide over the teeth of the ratchet wheel. It will thus be evident that on each reciprocation of the concentrator a partial revolution will be communicated to the shaft 7 which motion will in turn be transmitted 75 to the belt 6, by which the belt will be intermittently moved, the feed motion of the same being properly timed to allow the metalliferous particles in the material to feed to the screens during the concentrating 80 action preparatory to collection and discharge. Suitably mounted upon the machine is a check pawl or dog 41 operating to prevent reverse motion of the ratchet wheel, while permitting it to be fed up by the dogs 85 or pawls 35 and 36. In some cases it is desirable to reduce the speed of the belt when working on very low grade material. This may be conveniently accomplished, as shown in Fig. 10, by the use of spur gearing 42 between 90 the ratchet wheel and shaft 7, the gearing being properly proportioned to secure the desired effect.

The tailings or waste material passing over the last riffle of the deck and upon the final plate or inclined surface of the table discharges through a chute or outlet 43 into any suitable receptacle, and it will be understood that in the use of discharge slots in the belt in place of the channels 9' the concentrates will pass directly through a screen and the slot in the top stretch of the belt and discharge upon the upper surface of the lower stretch of the belt, the scraper 15 operating to force the concentrates off said 95 lower stretch of the belt for discharge through the outlet 16 and to prevent the same from passing between the belt and pulley or roll 5^a. If desired, the concentrates may discharge through the outlet 16 into a 100 collection chamber or casing 44 having an outlet door 45 adapted to be locked to prevent surreptitious removal of the concentrates. This collection chamber may be provided with a window or observation panel 105 46 to enable the operator to determine when the chamber is full.

From the foregoing description, taken in connection with the accompanying drawings, the construction and mode of operation 110 of my improved concentrator will be readily understood. This concentrator is especially useful and efficient for abstracting the gold in arid or semi-arid sections, as it will efficiently concentrate the material dry and without the use of any water. It will 115 also work as efficiently when using water, the water being fed in the ordinary way with the material to be treated. With this 120 125 130

concentrator, however, but a small amount of water is required compared with others, the continual supply of water being unnecessary to carry the material through the machine, since each section of the deck has a separate action similar to the ordinary miner's gold pan, the advantages of which will be evident. Furthermore, it will be seen that the invention provides a means whereby the material is subjected to thorough agitation in such a way as to secure the positive concentration of all particles of mineral matter, thereby avoiding waste and enabling even very low grade material to be successfully treated.

I claim:—

1. A concentrator comprising a receptacle provided with a working deck, said deck having a series of longitudinally spaced concentrated pockets provided with bottom outlets, an endless belt having its upper stretch arranged to travel below said outlets and normally closing the same against the escape of the material, said belt being provided at intervals with portions constructed to permit discharge of the material from the outlets, means acting upon the upper stretch of the belt for supporting and guiding said stretch with relation to the outlets, means acting upon the lower stretch of the belt to hold the same from depression, and a resiliently mounted scraper acting upon the upper surface of the lower stretch of the belt.
2. A concentrator having its deck or platform divided by riffles into a plurality of working sections, the surface of the bottom of each section being inclined downward toward the outlet end of the machine, a discharge screen at the bottom of each outlet section, and an endless conveyer or apron moving in contact with the underside of and controlling the discharge of the material through the screens.
3. A concentrator having a deck or table formed by a series of downwardly and forwardly inclined surfaces, riffles adjacent the lower forward ends of said surfaces and forming therewith pockets, screens at the base portions of the pockets, and an endless apron moved in rubbing contact with the undersides of the screens for controlling the discharge of the material through said screens.
4. A concentrator having a series of riffles, inclined conducting plates between the riffles and spaced therefrom to form pockets, screens at the base portions of the pockets formed by the plates and riffles, and a movable element traveling in rubbing contact with the under sides of said screens for controlling the discharge of the material through said screens.
5. A concentrator having a table formed of a plurality of inclined surfaces, riffles

spaced therefrom to form pockets and screens at the base portions of the pockets formed between said inclined surfaces and riffles, an endless apron normally closing said screens and movable in contact therewith and provided with outlets for controlling the discharge of the material there-through, and means for imparting intermittent motion to the apron.

6. A concentrator having a deck provided with a series of working surfaces, screens for the discharge of the material therefrom, an endless apron arranged to travel in rubbing contact with the undersides of the screens and controlling the discharge of the material through said screens, said apron being formed of a material having a friction surface and having portions cut away for the passage of the material, and means for imparting intermittent motion to the apron.

7. A concentrator having a deck provided with a series of working surfaces, each including a discharge screen, an endless belt controlling the discharge of material through said screen, said belt having its upper stretch arranged to travel beneath the screens and normally close the same, means for holding the upper stretch of the belt against the screens, means for holding the lower stretch of the machine from flapping motion, and means for intermittently moving the belt.

8. A concentrator having its deck provided with a series of working surfaces, each including a discharge screen, an endless belt controlling said screen, said belt having its upper stretch moving in contact with the screens, means for supporting the lower stretch of the belt, and a scraper operating upon the lower stretch of the belt.

9. A concentrator including a reciprocatory or vibratory table having a plurality of working sections provided with discharge screens, an endless conveyer movable in rubbing contact with and controlling the discharge of the concentrates through said screens, pawl and ratchet mechanism for intermittently actuating said conveyer, and a gravity controlled device influenced by the reciprocatory or vibratory action of the table to operate said pawl and ratchet mechanism.

10. A concentrator including a reciprocatory or vibratory table provided with a series of working sections, each including a pocket provided with a discharge screen, an endless apron controlling said screen, means for intermittently actuating said apron, and a gravity controlled vibratory agitator having spring tines depending into the pocket to agitate the material therein.

11. A concentrator including a vibratory table having a plurality of working sections, each provided with a discharge screen,

an endless apron controlling the discharge of the concentrates through said screens, means for vibrating the table, gravity controlled means affected by the vibrations of the table to intermittently move the apron, and agitators provided with spring tines to agitate the material on the table above the working portions thereof, and gravity con-

trolled means influenced by the vibrations of the table to vibrate said agitators.

In testimony whereof I affix my signature in presence of two witnesses.

CHARLES EDWARD BEYER.
